US0D1073447S

(12) **United States Design Patent** (10) Patent No.: **US D1,073,447 S**
(45) Date of Patent: ** May 6, 2025

(54) **HOSE CONTAINER**

(71) Applicant: **Larry Ray Buck**, Fort Worth, TX (US)

(72) Inventor: **Larry Ray Buck**, Fort Worth, TX (US)

(**) Term: **15 Years**

(21) Appl. No.: **29/905,029**

(22) Filed: **Oct. 16, 2023**

(51) LOC (15) Cl. **08-01**

(52) U.S. Cl.

USPC **D8/359**

(58) **Field of Classification Search**

USPC D8/354, 356, 349, 358, 359
CPC B66D 3/14; B65H 75/48; B65H 75/40;

B65H 49/322; B65H 75/4405

(57) **CLAIM**

The ornamental design for a hose container, as shown and described.

DESCRIPTION

FIG. 1 is an upper perspective view of a hose container showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
